UNITED STATES PATENT OFFICE.

ORA A. COLBY, OF IRWIN, PENNSYLVANIA, ASSIGNOR TO WESTINGHOUSE ELECTRIC & MANUFACTURING COMPANY, A CORPORATION OF PENNSYLVANIA.

ELECTRIC IRON.

Application filed March 10, 1922. Serial No. 542,610.

To all whom it may concern:

Be it known that I, ORA A. COLBY, a citizen of the United States, and resident of Irwin, in the county of Westmoreland and 5 State of Pennsylvania, have invented a new and useful Improvement in Electric Irons, of which the following is a specification.

My invention relates to electrically heated apparatus and particularly to electric irons 10 and it has for one of its objects to provide a relatively simple and inexpensive unitary heating element for an electric iron that may be easily and quickly assembled and disassembled and that may be quickly placed 15 in and removed from its operative position in the iron.

Another object of my invention is to provide a unitary heating element so constructed as to reduce the amount of heat 20 that may be radiated or transmitted to the handle member of the iron.

Another object of my invention is to provide a terminal plate construction for the heating element that shall co-operate with 25 an automatic circuit-interrupting device located in the terminal casing to insure its proper operation and that shall provide a relatively simple terminal construction for an electric iron.

30 In practising my invention, I provide a sole plate with integral lugs on its upper surface and locate thereon a pair of refractory plate members, the lower one being provided with a plurality of resistor-containing 35 grooves in its upper surface, and the upper one being provided with means for holding it in its proper operative position on the lower refractory member and acting as a cover member for the resistor. The lower 40 refractory resistor-supporting member is constructed of a material which will easily conduct the heat from the resistor to the upper surface of the sole plate and the upper refractory plate is constructed of a refractory heat-insulating material to reduce the 45 flow of heat in an upward direction. I provide a cover member which is suitably secured against the top of the sole plate and is provided with resilient means for pressing 50 the upper refractory plate against the lower plate and for pressing the lower plate into close engagement with the upper surface of the sole plate. I provide also the usual handle member suitably secured to 55 the cover member.

I provide a plurality of terminal plates which are removably mounted on the refractory resistor-supporting plate and I provide means thereon for electrically connecting thereto a circuit-interrupting device mounted in a metallic casing located at the back of the iron which casing is suitably secured 60 against one of the handle straps.

In the single sheet of drawings, Figure 1 is a view, partly in side elevation 65 and partly in section, of an electric iron embodying my invention;

Fig. 2 is a top plan view of the refractory resistor-supporting member;

Fig. 3 is a top plan view of the refractory 70 cover plate, and

Fig. 4 is a view, in vertical lateral cross-section, through the two plates when in their proper operative relation to each other, on the line IV—IV of Figs. 2 and 3. 75

An electric iron, designated generally by the numeral 11, comprises a working member or sole plate 12 which may be substantially triangular in outline and provided, on its upper surface, with an integral lug 80 13 located near the front point thereof and with a lug or a plurality of lugs 14 located at the rear edge thereof. A metallic cover member 15, the bottom edge of which has a contour substantially the same as that of the sole plate 12, is mounted on the sole plate and held thereagainst by a bolt 16. A handle member 17 is secured on the cover member 15 by a front handle strap 18 and a rear handle strap 19, the lower ends of 85 which are suitably secured to the cover member by rivets 21.

A refractory resistor-supporting plate 22, somewhat smaller in lateral dimensions but of substantially the same outline as the 95 plate 12, has its lower surface located in close operative engagement with the top surface of the sole plate 12 and is prevented from either longitudinal or lateral movement relatively thereto by the integral upstanding lugs 13 and 14. A plurality of grooves 23 and 24, which may be of any suitable extent and location, are provided in the upper surface of the member 22 to permit of locating therein a resistor member 25 which, as illustrated more particularly in Fig. 2, may comprise a suitable resistor wire wound into helical form. In order to permit of radiating at least a portion of the heat generated by the resistor 25 directly against the

upper surface of the sole plate 12, I provide slots 26 in that portion of the resistor-supporting member 22 immediately below the grooves 23 and 24 and these slots are of lesser extent than the lengths of the grooves 23 and 24 to provide material for holding the member 22 together. While I have indicated the grooves 23 and 24 as following, in general, the outline or contour of the plate 22, any suitable or desired configuration of grooves and location thereof may be employed. The refractory resistor-supporting member 22 comprises a material which is highly heat-conducting so that the heat generated by the resistor 25 is readily conducted to the top of the sole plate 12.

A relatively thin refractory cover plate 27, of substantially the same contour and outline dimensions as the member 22, is located on the upper surface of the plate 22 and is provided with integral, relatively small, depending lug portions 28 and 29 which fit into a portion of the groove 24 to maintain the plate 27 in its proper operative position relatively to the plate 22 and prevent lateral or longitudinal motion of the one relatively to the other. The location of the depending lugs 28 and 29 is, of course, such as to co-operate with, and fit into, parts of the groove 24 to attain the desired end. Each of the members 22 and 27 is provided with a substantially central opening 31 to permit of the bolt 16 extending therethrough into the sole plate 12 to hold the cover member 15 against the plate. The material of the cover plate 27 is such as to be substantially non-heat-conducting in order to reduce the flow of heat upwardly from the resistor member 25 to insure that the cover of the iron and the handle member shall operate at as low a temperature as possible.

A plurality of terminal straps 32, of substantially U-shape, are removably mounted on the refractory resistor-supporting member 22 at the rear end thereof by means of bolts 33 extending through openings 34 in the refractory plate, a nut 35 being operative to hold the bolt in position. If desired, that portion of each of the terminal straps engaging the upper surface of the plate 22 may be provided with a down-turned end 36 which is located in corresponding depressions 37 in the upper surface of the plate to prevent any turning movement of the terminal straps relatively to the refractory plate. The upper refractory plate 27 is provided with an end recess 38 to permit of the terminal straps extending therethrough.

Any suitable or desired method may be employed to hold the heating element, comprising the lower refractory plate 22, the upper refractory cover plate 27 and the resistor member located therebetween, in its proper operative position against the upper surface of the sole plate 12 but I prefer to

use some resilient means, such as a plurality of spring members 39, one end of each of which is secured against the under side of the cover member 15 by rivets 21 with the other end operatively engaging the top refractory plate.

A metallic terminal casing comprising an inner portion 41 and an outer cover portion 42 is located at the rear of the iron, the inner part 41 being secured against the handle strap 19 by one or more machine screws 43. The outer or cover part 42 may be secured against the inner part by one or more screws 44 which may also be effective to securely clamp the entire terminal casing against the handle straps.

An automatic and manual circuit-interrupting member is located in the terminal casing and comprises a relatively small tubular member 45, of substantially U-shape, in which is located a quantity of mercury 46 and which is provided with terminal leads 47 and 48 located at the bottom of one of the legs and near the top thereof to normally operatively engage the mercury 46. The member 45 is preferably held in its proper operative position by means of the conducting leads 47 and 48, the lead 47 being secured, at its outer end, against the upper end of one of the terminal straps 32 by means of a screw 49. The outer end of the conducting lead 48 is secured against the insulating plate 51 located on the inner surface of the inside of the terminal casing by a screw 52 which is effective, at the same time, to connect to the lead 48 one end of the lead 53 of the twin supply-circuit conductor 54. The end 55 of the second conductor is suitably connected to the other terminal strap 32 in a well known manner. If desired, a coil-spring member 56 may be located around the portion of the supply-circuit conductor 54 immediately outside of the end of the terminal casing, to prevent undue kinking or bending of the conductors, in a manner well known in the art. The lower end of the circuit interrupting device 45 extends through an opening 57 in the cover member 15 to permit of the mercury located at the bottom of the tube being vaporized when the temperature of the iron becomes unduly high, to thereby interrupt the circuit through the resistor 25. The circuit-interrupting device hereinbefore described is claimed in my copending application, Serial No. 503,796, filed September 28, 1921.

The device embodying my invention thus provides a relatively simple unitary heating element which may be manufactured at a relatively low cost, be easily and quickly assembled and be easily and quickly placed in its operative position in the iron or removed therefrom. The means provided for locating the unitary heating element on the sole plate is effective, while, at the same time,

not hindering either the mounting or dismounting of the heating element. The entire iron may be quickly disassembled and a damaged heating element replaced by a new one within a very short time.

Various modifications may be made in the device embodying my invention without departing from the spirit and scope thereof and I desire that only such limitations shall be placed thereon as are imposed by the prior art or are specifically set forth in the appended claims.

I claim as my invention:

1. An electric iron comprising a sole plate, a refractory resistor-supporting means on said sole plate, a resistor member located in said refractory means, a refractory heat-insulating plate located on said refractory resistor-supporting means and provided with integral means interfitting therewith for maintaining it in proper operative position relatively thereto, a cover member and resilient means on said cover member for pressing said heat-insulating plate against said resistor-supporting means and for pressing said resistor-supporting means against said sole plate.
2. An electric iron comprising a sole plate, a cover member therefor, a refractory heat-conducting resistor-supporting member on said sole plate, embodying means on said sole plate for maintaining said refractory member in proper operative position on said sole plate longitudinally thereof, a resistor member located in said refractory member, a refractory heat-insulating plate located on said resistor-supporting member and having

integral means for maintaining it in proper operative position relatively thereto, terminal plates for said resistor mounted on 40 said resistor-supporting member at the rear end thereof, resilient means on said cover member for pressing said heat-insulating refractory plate against said resistor-supporting member and for pressing said resistor-supporting member against said sole plate and a single means for holding said cover member against said sole plate and for preventing lateral movement of either of said refractory plates relatively to said sole plate. 50

3. An electric iron comprising a refractory heat-conducting resistor-supporting member, a resistor located removably thereon, and a refractory heat-insulating plate located on said resistor-supporting member 55 and having integral means interfitting therewith for maintaining it in proper operative position thereon.

4. In an electric iron, in combination, a unitary heating element comprising a refractory heat-conducting resistor-supporting bottom plate, a resistor member located thereon, a refractory heat-insulating top plate located on said bottom plate and having integral means interfitting therewith for 60 maintaining it in proper operative position on said bottom plate and a plurality of terminal plates secured to said bottom refractory plate.

In testimony whereof, I have hereunto 70 subscribed my name this 20th day of February, 1922.

ORA A. COLBY.
